US00D966336S

(12) United States Design Patent (10) Patent No.: US D966,336 S
Andre et al. (45) Date of Patent: * Oct. 11, 2022

(54) DISPLAY SCREEN OR PORTION THEREOF WITH ICON

(71) Applicant: Apple Inc., Cupertino, CA (US)

(72) Inventors: Bartley K. Andre, Palo Alto, CA (US);
Alan C. Dye, San Francisco, CA (US);
Aurelio Guzmán, San Jose, CA (US);
Christopher Wilson, San Francisco, CA (US)

(73) Assignee: Apple Inc., Cupertino, CA (US)

() Term: 15 Years

(21) Appl. No.: 29/805,802

(22) Filed: Aug. 30, 2021

Related U.S. Application Data

(63) Continuation of application No. 29/768,544, filed on Jan. 29, 2021, now Pat. No. Des. 929,449, which is a continuation of application No. 29/613,745, filed on Aug. 13, 2017, now Pat. No. Des. 909,410.

(57) CLAIM

The ornamental design for a display screen or portion thereof with icon, as shown and described.

DESCRIPTION

The FIGURE is a front view of a display screen or portion thereof with icon showing the claimed design.

The broken lines in the FIGURE show a display screen or portion thereof, and form no part of the claimed design.

1 Claim, 1 Drawing Sheet
